UNITED STATES PATENT OFFICE.

BENJAMIN F. LINDSLEY, OF MANSFIELD, OHIO.

SWING STAND.

Application filed April 23, 1926. Serial No. 104,120.

This invention relates to a stand for supporting a swing or hammock. One of the objects of the invention is to construct a frame or stand of tubular members for supporting a swing or the like, the stand being provided with a pair of U-shaped supporting members or the like which are maintained in rigid vertical positions by a bracing mechanism that permits 10 the usual front frame brace to be omitted, leaving the floor or the like between the supporting member free and unobstructed.

A further object is to provide means for firmly and rigidly bracing the standards in 15 spaced apart relation to each other, to prevent the members from being spread apart, sprung inwardly or otherwise distorted, especially when the stand is being moved from place to place.

20 A further object is to provide means for disconnecting the brace members from the supporting members to permit the brace members to be folded compactly for shipping and storage purposes in contact with 25 the rear brace, to conserve space and for convenience in handling the parts.

Further objects consist in providing 30 means for bracing the standards and maintaining same in normal positions without the necessity of using the usual front floor brace, which ordinarily is attached to the front portions of the supporting members, thereby permitting the user to walk to and from the swing without raising the feet, in 35 avoiding the interference of the usual front brace, stubbing the toes of the user in stepping in or out of the swing or the like, and further providing a free and unobstructed area of open space between and in front of 40 the standards to permit of sweeping or the like between the standards without interference.

Another object is to provide means for 45 constructing a swing stand with a minimum cost of material and labor and at the same time constructing a stand that is rigidly and firmly braced to maintain its normal position without the necessity of using an overhead bracing means.

50 Other objects are to provide a swing stand that is convenient to assemble for use; that is convenient for knocking down for storage and to save storage space; to construct a swing stand that can be assembled or disassembled without the use of screws, bolts or the like, thereby making it unnecessary to

remove or replace any of the parts, saving time and eliminating the annoyance caused in performing said operations.

These and other objects are attained by 60 the mechanism illustrated in the accompanying drawing in which:

Fig. 1 is a front elevation of the stand showing it assembled and also showing the brace rods in full lines when in use and in 65 dotted lines when in folded position.

Figure 2 is a view showing a part of one supporting member and a brace rod in section, the tubular end of a front portion of 70 a supporting member being shown fitted over a plug, providing a socket connection.

Figure 3 shows a hollow elbow used for connecting the rear portions of the supporting members to a tubular floor member.

Figure 4 is a sectional view showing 75 means for pivotally connecting one end of diagonally arranged brace rods to a tubular floor member, and the position of the braces when folded to the positions shown in dotted lines Figure 1.

In the drawings the invention is applied to a conventional swing stand. Reference numerals 1 and 2 represent the front upwardly extending portions of the U-shaped stand supporting members, and 3 and 4 represent the rear portions of the U-shaped supporting members of the stand. The supporting members are preferably made tubular in construction to provide a swing stand of light weight and for purposes that will 80 be described.

Hollow elbows 5 and 6 are provided to receive and engage the portions 3 and 4 of the supporting members and connect same to a tubular floor member 7 which is arranged to 95 lie adjacent to the floor or the like, thereby holding the U-shaped supporting members in vertical positions and in predetermined spaced relation to each other.

Brace rods 8 and 9 (preferably of flat construction) are provided and pivotally connected to the tubular floor member 7 by rivets 10 and 11 at one end to permit the braces to be swung to folded positions when desired as shown in Figure 1 in dotted lines 100 to save space for storing and shipping the swing stands.

The rods 8 and 9 are connected to the tubular floor member 7 and are arranged in diagonal positions with respect to the front 110 of the swing stand. The free ends of the brace rods are (preferably) made flat and

provided with plugs 12 and 13 which are riveted or otherwise fastened to the ends thereof, and arranged thereon in vertical positions. Attention is called to the fact 5 that the rear members 3 and 4 are connected together by a tubular floor member 7 and sockets 5 and 6, thereby holding same in alined and spaced apart relation with respect to each other. The pivoted brace 10 members 8 and 9 when connected by the plugs 12 and 13 to the parts 1 and 2 hold and maintain the frame work of the stand rigidly, preventing yielding of the parts comprising the stand with respect to each 15 other, distortion, vibration or the like, when subjected to strain.

It will also be noted that the portions of 20 the supporting members comprising the parts 1, 2, 3 and 4 can be lifted from their socket elbows and plug connections when desired, without withdrawing or removing any bolts, parts, screws or the like and assembling in the same manner.

In preparing the swing stand for shipment 25 or storage the supporting members are lifted up and withdrawn from their socket elbows and plug connections in the first instance then the diagonally arranged brace rods 8 and 9 are swung to the folded positions, as shown in Figure 1 in dotted lines. When it is desired to erect or assemble the stand for use, the diagonal arranged brace rods 8 and 9 are swung to the positions shown in full lines in Figure 1 and the plugs 30 12 and 13 are then inserted in the ends of the front portions 1 and 2 of the supporting members and the portions 3 and 4 thereof inserted in the hollow elbows. The stand is then ready for use.

40 It will be noted that in assembling or dissembling the swing stand for use, storage or shipping that no parts need be taken off, or put on the stand, thereby conserving time and making it convenient to erect or assemble; and that no parts of the mechanism are liable to be lost or mislaid as all parts are connected together preparatory to combining same in assembled positions.

Attention further is called to the fact 50 that, in constructing the swing stand or the like, substantially of tubular members, a swing stand is provided of minimum weight and maximum strength, while at the same time

means are provided to maintain the stand and its parts firmly and rigidly in position 55 counteracting the strains or springing of the parts that the stand is subjected to in use, or when the stand is changed or shifted from place to place.

What I claim is:

1. In a foldable stand for swings and the like, a pair of tubular standards which are provided with spaced apart integral leg members, a tubular floor member, elbow sockets attached to the floor member and 65 adapted to receive one leg of each standard, brace rods pivoted to the floor member and adapted to be connected at their free ends to the other legs of the tubular standards.

2. A foldable stand for swings and the 70 like comprising two end standards each composed of two substantially vertical legs rigidly connected at their tops, a rear floor member, an elbow socket at each end of the floor member, each socket turnably and 75 detachably receiving one leg of an end standard so that the standards may be swung into substantially a common plane with the floor member or outwardly at an angle thereto, and braces pivoted to the floor member and 80 detachably connected to the other legs of the end standards to hold them in the outwardly extending position.

3. A foldable stand for swings, comprising 85 end standards each having spaced leg portions, a floor member, sockets rigidly secured to the ends of the floor member and formed to removably receive and support one leg of each of the standards, braces pivotally connected to the floor member and 90 means carried by each brace to removably engage with the ends of the remaining leg of the standards to fit said standards relative to the floor member.

4. A foldable stand for swings comprising 95 end standards having spaced lower terminals, a floor member, sockets carried by the respective ends of the floor member to removably receive one terminal of each standard to thereby rotatably support the 100 standards, and braces carried by the floor member to removably cooperate with the remaining terminal of each standard to fix said standards relative to the floor member.

In testimony whereof I affix my signature.

BENJAMIN F. LINDSLEY.
